BELT OR SIMILAR ARTICLE

Louis L. Blumenfeld, Newark, N. J.

Application December 3, 1949, Serial No. 6,399

Term of patent 14 years

(Cl. D3—10)

To all whom it may concern:

Be it known that I, Louis L. Blumenfeld, a citizen of the United States, residing in Newark, Essex County, New Jersey, have invented a new, original, and ornamental Design for a Belt or Similar Article, of which the following is a specification, reference being had to the accompanying drawing, forming a part hereof.

Fig. 1 is a plan view of a belt, showing my new design;

Fig. 2 is a rear perspective view thereof as it appears in use;

Fig. 3 is a front view of the belt shown in Fig. 2; and

Fig. 4 is a side view thereof.

I claim:

The ornamental design for a belt or similar article, as shown.

LOUIS L. BLUMENFELD.
